UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

COAL-MINING APPARATUS.

Application filed October 7, 1922. Serial No. 593,094.

The present invention relates to certain new and useful improvements in coal mining apparatus, and particularly to apparatus comprising devices adapted to operate on the longwall system, to form kerfs at the base of a mine wall, associated with means actuated by the motor of the kerf forming mechanism, for its transportation from one working place to another.

10 In the mining of coal there has been developed a number of systems of mining, each radically different from the others, and entailing radically different arrangement of the chambers and passages of the mine. 15 The machines which have been devised for use in any one of these systems of mining have been unsuitable for operation in either of the others, such machines being characteristic of the systems of mining for which 20 they are intended. The system employed in any particular locality depends largely upon the character of the coal vein and of the overlying strata. Where the roof conditions are such as to require the placing 25 of numerous timbers in close proximity to the working face the longwall system of mining is commonly used. Mining machines designed for use in the longwall system have relatively long and narrow main frames 30 adapted to pass between the roof supporting timbers and the coal face. The actuating mechanism of the mining machine is mounted within the main frame and the cutting devices project therefrom to engage the coal 35 to cut it. The main frame of such a machine commonly rests directly upon the mine floor and its relatively long side walls are subject to sliding contact with the face of the coal vein and the roof supporting timbers. 40 As such machines are designed to operate in either direction both sides of the frame are subject to such sliding contact and they should be without lateral projection. In order that such machines may be 45 conveniently and expeditiously transferred from one working place to another, wheeled trucks are provided upon which the machine may be conveniently loaded.

It is the especial object of this invention 50 to provide, in an apparatus of the class described, improved power transmitting devices adapted to connect the motor of the mining machine with the wheels of the truck to propel said truck along the mine tracks. 55 The means whereby I attain this object

are fully described in the following specification and illustrated in the accompanying drawings of which,

Fig. 1 is a side elevation of a mining machine and truck equipped with the devices 60 of my invention, in operative relation for transportation from one working place to another.

Fig. 2 is a plan view of the machine illustrated in Fig. 1.

Fig. 3 is a rear end elevation partly in section of the devices illustrated in Figs. 1 and 2.

Fig. 4 is a fragmentary sectional view 70 taken along the line IV—IV of Fig. 2.

Fig. 5 is an end view of the auxiliary transmission device when removed from the mining machine.

Fig. 6 is a side elevation of the truck element of the apparatus in position to receive 75 the mining machine.

Fig. 7 is a fragmentary sectional view showing a detail of the truck mechanism.

Like numerals refer to similar parts in the several figures.

As shown in the drawings the numeral 1 indicates as an entirety, a longwall mining machine of well known design, and the numeral 2 indicates a truck adapted to the transportation of said mining machine from 80 one working place to another.

The mining machine here illustrated comprises a relatively long and narrow main frame 3 having a bottom 4 adapted to rest upon and slide over the mine floor, and vertically extending side walls 5 and 6 adapted to contact with and slide along the working face of the coal vein. At its rearward end there is pivotally supported an elongated horizontally extending cutter arm 7 adapted 95 to project from either side of the main frame and to swing across its end from positions at one side of the machine to positions at its other side. A motor which may be of any preferred type suitable to the conditions under which the machine operates, is mounted upon the middle portion of the main frame. For purposes of illustration I have here shown an electric motor 8 adapted to receive its actuating current through 100 a suitable conductor cable 9 from any convenient source of electric supply. Controlling mechanism is provided for the manipulation of the motor 8 which may be of any preferred design, but as such devices are 105 110

well known in the art and form no part in the present invention their illustration and description at this time is not thought to be required. The armature shaft of the 5 motor 8 extends rearwardly at 10, and is connected by suitable gearing, not shown in the drawing, with the cutting mechanism 7 to actuate it, and at its forward end the armature shaft is extended at 11 to actuate the feeding mechanism.

The feeding mechanism comprises a winding drum 12 upon which is windable a feed rope 13, the free end of which is adapted to be connected with any suitable abutment to- 15 wards which the machine will be bodily drawn by the winding of said rope. The drum 12 is adapted to rotation about a vertical axis and is arranged to be connected by a suitable friction clutch mechanism un- 20 der the control of the hand wheel 14, with a spur gear 15. The spur gear 15 engages a spur pinion 16 fixed to the vertical shaft 17. To the vertical shaft 17 there is also fixed 25 a ratchet wheel 18 and this ratchet wheel is engaged by a pawl 19 mounted upon a rocker arm 20. A connection rod 21 connects the rocker arm 20 with a crank 22 fixed to the upper end of a vertical shaft 23. The shaft 23 is journaled in bearings of the main 30 frame, and carries a worm wheel 24 which engages the worm 25 fixed to the armature shaft extension 11. By rotation of the crank 22 the rocker arm 20 is oscillated to rotate the ratchet wheel 18 and drive the gear 15 35 from which the drum 12 may be actuated by manipulation of the hand wheel 14.

The truck 2 comprises a structural steel frame 26 having journal bearings 27 and 28 in which are journaled the axles 29 and 30 40 for the support of the truck. To the axles 29 and 30 are fixed traction wheels 31 adapted to travel along the rails 32 of the mine track. A sprocket wheel 33 fixed to the axle 29 is adapted to be connected by a suitable endless chain 34 with the sprocket wheel 35 projecting from the side of the mining 45 machine frame when said mining machine is in traveling position upon the truck. Power may thus be derived from the motor 50 of the mining machine to actuate the track wheels 31 and the axles 29 and 30 are connected together by a suitable endless chain 36, in the manner well understood in the art, to increase the tractive effort of the 55 truck.

The truck frame 26 comprises the longitudinally extending angle bars 37 which constitute guideways along which the machine may be moved to and from traveling 60 position, and upon which the machine may be supported for transportation. Slidable upon the angle bars 37 is a secondary guide frame having longitudinally extending angle bars 38 adapted to extend from the rear- 65 ward end of the angle bars 37 to the mine

floor to guide the mining machine on to and off of the track. Hinged to the forward end of the auxiliary guide frame 38 is a latch 39 adapted to engage the cross member 40 of the truck frame to limit rearward motion of the auxiliary frame 38 relative to the truck frame. The upturned flange of the cross member 41 of the auxiliary frame is adapted to engage the forward end of the mining machine as it is drawn onto the 70 truck to drag said auxiliary frame forwardly of the truck frame to lie beneath the mining machine when it is in traveling position.

To load the mining machine onto the 80 truck the auxiliary guide frame 38 is first adjusted, as illustrated in Fig. 6, with its rearward end resting upon the mine floor. The feed rope 13 is then attached to the abutment 42 rigidly secured to the forward 85 end of the truck frame 37, and the feed mechanism is actuated to wind the feed rope 13 upon the drum 12. The tension thus applied to the feed rope 13 draws the mining machine longitudinally of the auxiliary guide frame 38 until its forward end 90 engages the cross member 41 after which the mining machine and the auxiliary frame are together drawn forwardly along the guide ways 37 into traveling position upon 95 the truck.

To unload the mining machine from the truck, the feed rope 13 is drawn out from the winding drum, carried rearwardly along the side of the machine and attached to a suitable abutment in the rear of the truck towards which the mining machine and the auxiliary frame 38 will be drawn by tension of the feed rope 13. As the center of gravity of the mining machine passes the end 100 of the truck frame 37 the auxiliary guide frame 38 tilts with the mining machine, and its rearward end contracts with the mine floor to afford an inclined skid down which 105 the mining machine may be drawn to the 110 mine floor.

As the side walls 5 and 6 of the mining machine frame are both subject to sliding contact with the face of the coal vein, it is apparent that they should be without lateral projections, and for that reason I have provided a peculiar arrangement of parts whereby the sprocket wheel 35 may be conveniently arranged at the side of the mining 115 machine frame when it is desired to establish power connections between the mining machine and the truck wheels, and may be readily removed therefrom during the operation of the mining machine. Formed in the mining machine frame is a journal bearing 43 which extends through the side wall 5, and in this journal bearing is mounted a rotary member 44 which is positioned entirely within the vertical bounding planes of the mining machine frame. At the inner 120

end of this member 44 is fixed a miter gear 45 which engages a similar miter gear 46 keyed to the crank shaft 23 from which power is derived for the rotation of the member 44. Formed in the member 44 is a socket 47 adapted to receive a stud shaft 48 formed integral with the sprocket wheel 35. A clutch member 49 formed upon the stud shaft 48 is adapted to engage with suitable 10 clutch teeth formed on the outer end of the member 44, and these clutch teeth are so shaped that rotative pressure between the members tends to hold the sprocket wheel 35 securely in operative position. When 15 said rotative pressure is removed the stud shaft 48 may be withdrawn from the socket 47 leaving the side of the machine frame without lateral projections.

I claim:

1. In mining apparatus, the combination 20 of a mining machine frame having a substantially vertical unobstructed side wall adapted to engage and slide along a coal face, coal cutting instrumentalities carried by said frame, a motor for driving said instrumentalities, a bearing wholly within the plane of said side wall, a transmission element insertable in said bearing so as to project outside of said side wall and connectable 25 with exterior auxiliary devices for driving same, and driving means connectable between said motor and said transmission element.

2. In mining apparatus, the combination 30 of a mining machine frame having a substantially vertical unobstructed side wall to engage and slide along the coal face, coal cutting instrumentalities carried by said frame, a motor on said frame to actuate said cutting devices, power transmission means operated by said motor, a bearing lying wholly within the plane of the side wall of said frame, an auxiliary power transmission device removably mounted in said bearing and projecting beyond the vertical side wall of said frame when in operative position, means for connecting said auxiliary device when in operative position with said power transmission means, a wheeled truck 40 on which said mining machine is transported, and driving connections between said auxiliary power transmission device and said truck.

3. In mining apparatus, the combination 45 of a mining machine frame having a substantially vertical unobstructed side wall to engage and slide along the coal face, cutting instrumentalities carried by said frame, a motor on said frame to actuate said cutting devices, power transmission means actuated by said motor and comprising a vertically disposed shaft, a bearing lying wholly within the plane of the side wall of said frame, a horizontally disposed rotary member 50 mounted in said bearing, driving connec-

tions between said vertical shaft and said rotary member, an auxiliary power transmission device removably connectable to said rotary member and projecting beyond the vertical side wall of said frame when in operative position, a wheeled truck on which said mining machine is transported, and driving connections between said auxiliary power transmission device and said truck. 70

4. In mining apparatus, the combination 75 of a mining machine frame having a substantially vertical unobstructed side wall to engage and slide along the coal face, cutting instrumentalities carried by said frame, a motor to actuate said cutting devices, power transmission means actuated by said motor and comprising a vertically disposed shaft, a bearing lying within the side wall of said frame, a horizontally disposed hollow shaft mounted in said bearing, driving connections between said vertical shaft and said hollow shaft, an auxiliary power transmission device removably mounted in said hollow shaft in driving connection therewith and projecting beyond the vertical side wall of said frame when in operative position, a wheeled truck on which said mining machine is transported, and driving connections between said auxiliary power transmission device and said truck. 85

5. In mining apparatus, the combination 90 of a mining machine frame having a substantially vertical unobstructed side wall to engage and slide along the coal face, cutting instrumentalities carried by said frame, a motor on said frame to actuate said cutting devices, power transmission mean actuated by said motor and comprising a vertically disposed shaft, a bearing lying within the side walls of said frame, a horizontally disposed hollow shaft mounted in said bearing, driving connections between said vertical shaft and said hollow shaft, a stud shaft removably mounted in said hollow shaft in driving connection therewith and projecting beyond the vertical side wall of said frame when in operative position, a wheeled truck on which said mining machine is transported, and driving connections between said stud shaft and said truck. 95

6. In mining apparatus, the combination 100 of a mining machine frame, a wheeled truck on which said mining machine is transported, a motor on said frame, power transmission devices comprising a vertically disposed shaft driven by said motor, a horizontally disposed hollow shaft mounted in bearings in said frame wholly within the side wall thereof, driving connections between said hollow shaft and said vertical shaft, a stud shaft removably mounted in said hollow shaft and interlocked for rotation therewith when in operative position, driving means on said stud shaft projecting 105 beyond the side wall of the frame when in 110

115

120

125

130

operative position, and driving connections between said stud shaft and said wheeled truck.

7. In mining apparatus, the combination of a mining machine frame, a wheeled truck on which said mining machine is transported, a motor on said frame, a power transmission device carried by said frame and having a horizontally disposed shaft, driving connections between said motor and said shaft, a horizontally disposed hollow shaft mounted in bearings in said frame wholly within the side wall thereof, gear connections between said hollow shaft and said vertical shaft, a stud shaft removably mounted in said hollow shaft and interlocked for rotation therewith when in operative position, a driving sprocket on said stud shaft projecting beyond the side wall of the frame when in operative position, and driving connections between said sprocket and said wheeled truck.

8. In mining apparatus, the combination

of a mining machine frame, a wheeled truck on which said mining machine is transported, a motor on said frame, a power transmission device having a vertically disposed shaft geared to the shaft of said motor, a driving gear on said vertical shaft, a horizontally disposed shaft mounted in bearings in said frame wholly within the side wall thereof and having a socket therein, a gear on said horizontally disposed shaft engaging the driving gear on said vertical shaft, a stud shaft removably mounted in the socket of said hollow shaft and interlocked for rotation therewith when in operative position, a driving sprocket on said stud shaft projecting beyond the side wall of the frame when in operative position, and driving connections between said stud shaft and said wheel truck.

In testimony whereof, I affix my signature.

NILS D. LEVIN.
